UNITED STATES PATENT OFFICE.

WILLIAM E. ADAMS, OF SALEM, MASSACHUSETTS.

POWER SYSTEM.

1,008,770.

Specification of Letters Patent. Patented Nov. 14, 1911.

Application filed August 5, 1909. Serial No. 511,293.

To all whom it may concern:

Be it known that I, WILLIAM E. ADAMS, a citizen of the United States, residing at Salem, in the county of Essex and State of Massachusetts, have invented certain new and useful Improvements in Power Systems; and I do hereby declare the following to be a full, clear, and exact description of the invention, such as will enable others skilled in the art to which it appertains to make and use the same.

The invention relates to power systems, and more particularly to means adapted to be used in connection with an internal combustion engine whereby the efficiency of the system is increased.

One object of the invention is to provide means for utilizing the waste heat from the internal combustion engine.

20 A further object is to provide improved means for utilizing compressed air to start the internal combustion engine.

With these ends in view, one feature of the invention contemplates the provision of 25 means for compressing air, which is then cooled and passed through a jacket which surrounds the internal combustion engine. The heated compressed air is further heated by the exhaust gases of the internal combustion engine, and is then utilized in an 30 air engine or motor.

A further feature of the invention contemplates the provision of an air compressor combined with an internal combustion engine so that the former may be utilized in 35 starting the latter, and improved means for controlling the supply of compressed air during the starting of the internal combustion engine and for supplying atmospheric 40 air during the normal running of the compressor.

Other features of the invention will be referred to in connection with the specific 45 description of the illustrated embodiment of the invention.

In the accompanying drawings, Figure 1 is a plan view of the apparatus applied to a motor vehicle; Fig. 2 is a side elevation of the same; Fig. 3 is a fragmentary vertical section taken on the line 3—3, Fig. 1, on an enlarged scale; Fig. 4 is a vertical section taken on the line 4—4, Fig. 1, showing one unit of the internal combustion engine in section; Fig. 5 is a vertical section taken 50 on the line 5—5 of the air controlling valve; Fig. 6 is a vertical section taken on line

6—6, Fig. 1; Fig. 7 is a partial horizontal section taken on line 7—7, Fig. 2; Fig. 8 is a horizontal section taken on line 8—8, Fig. 2; Fig. 9 is a fragmentary vertical section 60 showing the discharge valves of the air compressor.

As shown in the accompanying drawings, the apparatus is applied to a motor vehicle, but obviously certain features of it are 65 equally adaptable for use in other localities. The internal combustion engine is of the 2-cycle type and comprises two cylinders 10 and 11. Both cylinders are alike, therefore a description of one will suffice for both. 70 The cylinder 10 is mounted upon a crank case 12, which is provided with suitable bearings 14 within which the main shaft 15 is journaled. Said main shaft is provided at one end with a fly wheel 16. Within the 75 cylinder 10 is a cylinder head 18 through which a piston rod 20 reciprocates, and is suitably packed by the packing 21. A hollow piston 22 is secured to the upper end of the piston rod 20 and a piston 23 is secured to the lower end of said piston rod. A connecting rod 24 is secured to the piston 23 by means of a wrist pin 25 at one end, and is attached to the crank pin 26 at its other end. Surrounding the cylinder 10 80 is a casing 30 which is separated from the cylinder to form a jacket or cooling chamber 31. This chamber surrounds the side walls and top of the cylinder 10, thus forming a cooling jacket for the engine and for 85 the air compressor which is at each side of the cylinder head 18 between said head and the pistons 22 and 23. A chamber 32 is formed within the cooling jacket 31 and communicates by means of the port 33 at 90 its lower end, with the interior of the crank case 12, and at its upper end by means of a port 34 with the interior of the compression and explosion chamber 35 of the internal combustion engine. A spark plug may 100 be mounted within the opening 36 by which the explosive charge within the chamber 35 may be ignited. An exhaust passage 38 communicates with the interior of the chamber 35 at one end and with a chamber 40 105 which is adjacent to a valve chamber 41 of the air engine. The exhaust gases from the internal combustion engine pass from the passage 38 through the chamber 40 and thence through openings 42 into the chamber 43 which surrounds the cylinders of the 110 air engine. From this chamber the exhaust

gases pass through the pipe 44 to a muffler 45 and thence to the atmosphere.

The air compressor is utilized in starting the internal combustion engine to obviate the necessity of "cranking". For this purpose compressed air is stored in the receiver or reservoir 50 which is connected by means of a pipe 51 to a valve chamber 52. In said chamber 52 is a cylinder 53 provided with two sets of ports 54 and 55 which are controlled by a piston valve 56 traveling within the cylinder 53 and operated by means of a piston rod 57 connected to an eccentric strap 58 on an eccentric 59 mounted upon the crank shaft 15. The piston valve 56 also controls the passages 60 and 61 which communicate with the chambers at the upper and lower sides, respectively, of the cylinder head 18. An exhaust passage 62 also communicates with the interior of the cylinder 53 and is prolonged by a pipe 64 which opens into the atmosphere. The pipes 51 and 64 are controlled by a double valve 134 mounted upon a stem 135 having a handle 136 at its upper end. A valve 65 mounted within a casing 66 on the side of the chamber 52 controls the admission of atmospheric air to the interior of the chamber 52, said valve opening inwardly to supply the air when the compressor is acting normally to supply compressed air to the system. The valve 56 thus operates to control the supply of compressed air to the air compressor when the compressor is used to start the internal combustion engine, and during the normal operation of the air compressor the valve is actuated to control the supply of atmospheric air to the compressor. The discharge of the compressed air from the air compressor is controlled by means of the valves 68 and 69 which open outwardly and communicate with a passage 70 which is connected to a pipe 71. This pipe 71 is connected at its other end with a cooling chamber 72. This cooling chamber is connected by means of a pipe 73 with the cooling jacket 31 of the internal combustion engine, and said cooling chamber 72 is also connected to the cooling jacket of the engine by means of a pipe 74 which branches at 75 to enter the top of the cooling jacket of each cylinder. The air from the cooling jacket 31 of the internal combustion engine passes through a pipe 76 within the chamber 40 and is discharged through openings 78 into the valve chamber 41 of the air engine.

The air engine is shown as composed of three units; a description of one will, therefore, suffice for all. The chamber 41 is divided longitudinally by a web 80 and a plurality of valve cylinders 81. The cylinders 81 are each provided with ports 82 and 83 which are controlled by a piston valve 84 having a piston rod 85 connected to a rocker arm 86 of a valve gear. The piston valves

84 control the ports 82 and 83 and thereby control the admission of air to the cylinders 88 which are also mounted within the chamber 41 and provided with ports 89 and 90 at their upper and lower extremities respectively. An exhaust passage 92 communicates with each of the valve cylinders 81 and all discharge into a pipe 94 which leads to a muffler 95. The chamber 41 is also connected by means of an air overflow pipe 96 to the compressed air tank or reservoir 50, said pipe being provided with a check valve 97. The purpose of this air overflow pipe is to conduct compressed air from the chamber 41 to the reservoir 50 when the air engine is stationary and the internal combustion engine is running. Said reservoir 50 is provided with a relief valve 98 which operates to allow the discharge of air from the reservoir when a predetermined pressure 85 has been reached therein.

Each cylinder 88 is provided with a piston 100 having a piston rod 101 connected to a hollow piston 102 which is provided with a wrist pin 103 about which the upper end of a connecting rod 104 is mounted. The lower end of the connecting rod 104 is secured to a crank pin 105 of a crank 106 on the main or crank shaft 107 of the air engine.

The piston valves 84 are controlled by means of a handle 110 attached to a sleeve 111 on the steering shaft of the motor vehicle. A crank arm 112 is connected to the sleeve 111 at one end and to a link 114 at the other end. Said link 114 is connected to a crank arm 115 secured to a shaft 116. This shaft extends longitudinally of the engine within the chamber 117 formed by a casing 118 upon which the chamber 41 is mounted. Secured to the shaft 116 are three sets of channelled links 120, one set for each cylinder. Within the channels 121 of these links, rollers 122 are adapted to travel. These rollers are mounted to rotate about a pin 123 carried by a link 124. Said link 124 is pivotally connected to the lower end of the connecting rod 86, and also pivotally connected to a link 125. Said link 125 is connected at one end to the connecting rod 104 and at its other end to a crank arm 126 mounted on a shaft 127. By moving the handle 110 a quarter turn in either direction from the central position the shaft 116 may be rocked, thus moving the piston valves within the cylinders 81, the direction in which they are moved determining the direction of rotation of the engine, as is well known. The above described valve gear is of well-known construction, and any suitable form may be employed if desired.

Connected to the eccentric strap 58 is a rod 130 which is connected to a spark timer 131. Said spark timer may be adjusted to advance or retard the spark by means of a 130

rod 132 connected thereto and extending to a convenient position for the operator of the machine.

The operation of the apparatus is as follows: It will be assumed that the reservoir 50 has been filled with compressed air. The handle 136 is turned to open the valve 134, thus allowing compressed air to flow through the pipe 51 into the chamber 52. The pressure of this air will maintain the valve 65 closed. With the parts in the position shown in Fig. 4, compressed air passes through the ports 55, and the passage 61, into the chamber at the lower side of the cylinder head 18, thus forcing the piston 23 downwardly. The air above the cylinder head 16 is forced out through the passage 60 and discharged through the exhaust passage 62 and the pipe 64. This cycle of operations is allowed to be repeated until the internal combustion engine compresses and explodes a charge in order to be driven by its own power. Thereupon the valve 134 is closed. The air for supplying the compressor is then admitted through the valve 65 and through the ports 54 and 55 alternately into the chambers above and below the cylinder head 18, and discharged from said chambers through the valves 68 and 69 into the pipe 71 and from thence to the cooling chamber 72. The air from the cooling chamber then passes through the pipes 73 and 74 to the engine cooling jackets 31, and from thence through the pipe 76 into the chamber 41. The air is then controlled by the piston valves 84 to drive the pistons 100 of the air engine. Said air engine may be connected by means of a universal joint 140 to the driving gear of the vehicle. The valve gear is manipulated by means of the handle 110 to cause the air engine to propel the vehicle forward or backward as is desired. If the air engine is stopped while the internal combustion engine is running, the compressed air is discharged from the chamber 41 through the air overflow pipe 96 into the reservoir 50 until such time as the pressure therein exceeds the predetermined limit, whereupon the relief valve 98 operates.

50 The supply of combustible mixture for the engine may be controlled by means of a well-known form of carburetor 150 which is provided with an air intake 151 and a gasolene supply 152 connected to a tank 153. Said carburetor may be controlled by means of a spring-pressed valve within a cylinder 155. Said cylinder communicates by means of a pipe 156 with the cooling tank 72, and the pressure within the tank acts upon a piston connected to the valve. As the pressure within the tank 72 increases beyond a predetermined limit, the valve 154 closes, thus reducing the speed of the engine, and as the pressure falls said valve opens under the influence of its spring, and thus increases

the speed of the engine. The combustible mixture is conveyed from the carburetor by a branch pipe 158 to the crank cases 12 of the internal combustion engine.

It is to be observed from the construction above set forth that the compressed air is first cooled and then utilized to cool the cylinder of the internal combustion engine and the air compressor thereby becomes heated, and said air is further heated by means of the exhaust gases within the chamber 40 before being utilized in the air engine.

While I prefer to employ the specific construction and arrangement of parts shown and described in embodying the various features of the invention in a simple and compact construction, it will be understood that this construction and arrangement is not essential to the invention in its broader aspect, and may be varied or modified as found desirable. It will also be understood that the various features of the invention may be embodied with advantage in systems which do not embody the other features, although improved results may be secured by embodying all the features in the same system.

Having set forth the nature and object of the invention, and specifically described one form of apparatus in which it may be embodied, what I claim is:

1. The combination with an internal combustion engine having an air jacket around its combustion cylinder, of an air compressor driven by the internal combustion engine and supplying air to the air jacket, an air reservoir connected with the air jacket to receive the heated and compressed air therefrom, and means coöperating with the air compressor for controlling a supply of compressed air from the reservoir to the air compressor to start the engine, substantially as described.

2. The combination with an internal combustion engine having an air jacket around its combustion cylinder, of an air compressor combined with the internal combustion engine, an air cooler connected to the air compressor and to the air jacket, an air engine, means for supplying heated air from said air jacket to the air engine, an air reservoir, means for supplying compressed air to the air reservoir, and means for supplying compressed air from said reservoir to said air compressor for starting the internal combustion engine, substantially as described.

3. The combination of a combined air compressor and internal combustion engine having the air compressor located between the compression and combustion chambers of the internal combustion engine, a valve chamber communicating with the air compressor, a valve within said chamber, means for supplying compressed air to said chamber, and means for supplying compressed air to said chamber.

ber, and means for moving said valve to control the air to utilize the compressor to start the internal combustion engine, substantially as described.

5. 4. The combination of a combined air compressor and internal combustion engine, a valve chamber communicating with the air compressor, a valve within the chamber for controlling the communication between the 10 air compressor and valve chamber, means for supplying compressed air to said valve chamber to be utilized in the air compressor to start the internal combustion engine, and a valve for admitting atmospheric air to 15 said chamber, substantially as described.

5. The combination of a combined air compressor and internal combustion engine, a valve chamber communicating with the air compressor, a valve within the chamber for 20 controlling the communication between the air compressor and the chamber, means operatively connecting the valve and the crank shaft of the engine, means for supplying compressed air to said valve chamber to be 25 utilized in the air compressor to start the internal combustion engine, and means for supplying atmospheric air to said valve chamber, substantially as described.

6. The combination of a combined air compressor and internal combustion engine, a valve chamber communicating with the air compressor, a valve within the chamber for 30 controlling the communication between the air compressor and the chamber, means operatively connecting the internal combustion engine and the valve, an air reservoir connected to the air compressor, means for 35 supplying compressed air from said reservoir to said valve chamber for use in the air compressor for starting the internal combustion engine, and means for supplying atmospheric air to said valve chamber, substantially as described.

7. The combination of an internal combustion engine having an air jacket, an air compressor driven by the internal combustion engine and capable of use in starting the said engine, an air cooler, means for conducting air from the compressor to the 45 cooler and from the cooler to the air jacket, as air motor, means for supplying the air

from the air jacket to the air motor, means for utilizing the exhaust gases from the internal combustion engine to heat the air supplied to the air motor, an air reservoir, and 55 means comprising an air overflow for conducting the compressed air from the air motor to the air reservoir when the air motor is stationary, and the internal combustion engine and air compressor are running, substantially as described. 60

8. The combination of an air compressor, an air reservoir, a valve chamber communicating with the air compressor and with the air reservoir, a mechanically operated valve 65 in said chamber for controlling the communication between said chamber and the air compressor, and a pressure operated valve for admitting atmospheric air to said chamber, substantially as described. 70

9. The combination of an air compressor, an air reservoir, means for conducting compressed air from the compressor to the reservoir, a valve chamber communicating with the air compressor and reservoir, an exhaust 75 passage communicating with said compressor, a mechanically operated valve in said chamber for controlling the communication between the chamber and the compressor and also controlling the exhaust passage, and a 80 pressure operated valve for admitting atmospheric air to said chamber, substantially as described.

10. The combination of a combined internal combustion engine and air compressor, 85 an air reservoir, means for conducting compressed air from the compressor to the reservoir, a valve chamber communicating with the air compressor and with the reservoir, a valve for controlling the communication 90 between the compressor and the valve chamber whereby compressed air may be utilized in the compressor for starting the internal combustion engine, and means for admitting atmospheric air into said chamber, substantially as described. 95

In testimony whereof I affix my signature, in presence of two witnesses.

WILLIAM E. ADAMS.
